UNITED STATES PATENT OFFICE.

GUSTAV A. HARTER, OF CHICAGO, ILLINOIS.

ELECTRIC-LIGHT FIXTURE.

1,250,580.

Specification of Letters Patent. Patented Dec. 18, 1917.

Application filed September 18, 1915. Serial No. 51,341.

To all whom it may concern:

Be it known that I, GUSTAV A. HARTER, a citizen of the United States, residing at Chicago, in the county of Cook and State of Illinois, have invented certain new and useful Improvements in Electric-Light Fixtures, of which the following is a specification.

This invention relates to electric fixtures, and more particularly to the mounting and manipulation of the shades and globes and the adjustment of the electric lamp support with respect to the other parts. The principal object of the invention is a provision of an improved construction, combination and arrangement by means of which the adjustment may be carried out.

In the accompanying drawings, Figure 1 is a view partly in section and partly broken away illustrating a construction which embodies the principal features of my invention; Fig. 2 is a sectional detail of the globe locking mechanism; Fig. 3 is a side elevation of the part shown in Fig. 2; Fig. 4 is a plan view of the socket-adjusting mechanism; Fig. 5 is a side elevation of the socket-adjusting mechanism; Fig. 6 is a sectional view taken on the line A—A of Fig. 1; Fig. 7 is a plan view of a modified form of socket-adjusting mechanism; Fig. 8 is a side elevation of the same; Fig. 9 is a view of the end of the socket-adjusting mechanism; Fig. 10 is a sectional view of a modified form of globe locking mechanism; Fig. 11 is a detail of the lock proper shown by Fig. 10; and Figs. 12 and 13 are plan and elevation views respectively of the screen protector clamping ring.

In order to provide an electric lamp fixture certain provisions must be made for accommodating both the old form of electric lamps with carbon filaments and also the newer nitrogen lamps, as well as for the different sizes of lamps of either kind. It is a well known fact that lamps must be raised or lowered with respect to their shades, globes and reflectors in order to produce the best lighting effects, and in order to produce various lighting effects.

In the present exemplification of my invention a housing or holder 5 is supported in any suitable manner, as for example, by being threaded on the extremity of a pipe or conduit 6, and is preferably constructed of sheet or cast metal with a projecting flange 7 at the top which partially covers

and forms a protection for the apertures 8 extending around the top of the housing. On the inside this housing or holder is formed with parallel ridges 9 spaced apart 60 to form a guide-way for the slotted extremities 10 of a socket holder 11. This socket holder is adjustable up and down the guide-ways and an adjusting screw 12 is threaded through a nut 13 which substantially fills the guide-way and prevents the nut from turning so that the socket holder may be readily held in any adjusted position in which it is placed.

This socket holder 11 is designed and intended to support sockets of various sizes. In the socket 14, shown by Figs. 1, 4 and 5, are recesses 15 at the top thereof for the reception of a nut 16. Terminals 17 and 18 are also provided at the top of the socket 75 for connection with the ordinary electric conductors. The socket holder 11 is formed with an upwardly extending yoke 19 of sufficient width to allow the socket 14 to slide freely therein the sides of the socket 80 being formed with grooves 14^a for the yoke so that it may be adjusted at various heights with respect to the yoke. The upright sides of the yoke are formed with slots 20 (see Fig. 5) with an enlargement 21 at the bottom and a screw 22 is inserted through the slot and through a suitable hole in the body of the socket 14 into the nut 16 at each side of the socket. These screws 22 may be adjusted to hold a socket at any desired height 90 with respect to the yoke, and the enlarged opening 21 at the bottom of the yoke enables one to remove the socket from the yoke without removing the screws 22 from the socket, by simply loosening them and sliding the 95 socket downward.

If it is desired to secure a smaller socket to the socket holder 11 a pair of socket clamping members 23, as shown in Figs. 7 and 8, may be employed. These members 100 23 have bent extremities 24 which engage over the sides of the yoke portion 19 and are held together by means of fastening devices 25. A socket 26 is inserted between them and by adjusting the fastening devices 105 25 this socket may be adjusted and held in any position with respect to the yoke, the members 23 being slidable with respect to the yoke and the socket 26 itself being slidable with respect to the members 23.

At the bottom of the holder 5 is a shade or reflector 27 which is preferably secured

to the holder at one side by means of a hinge. This hinge comprises a member 28 secured to the shade, another member 29 secured to the holder and a connecting link 30 hinged to both of the members. At the opposite side of the holder 5 it is provided with a catch 31 and pivoted to the shade is a latch 32 which may be hooked over the catch for holding the shade in position. This shade preferably has an upwardly extending portion 33 which extends within the holder at the bottom, and the object of the hinge above described is to prevent the shade from hitting an electric lamp 34, inserted in the socket when the shade is rotated about its hinge for any purpose. A globe 35 is usually inserted within the shade and in the present invention it is held in place by means of one or more fixed supports 36 projecting from the inside of the shade and by means of a locking member 37 preferably pivoted at the same place as the latch 32 of the shade latching device and extends through a suitable aperture 38 of the shade (see Fig. 2). This member 37 will remain in place as long as the upward projecting portion 33 of the shade is within the holder 5. As soon as this side of the shade is rotated downwardly so that the locking member 37 is free from contact with the end of the holder 5 this member 37 may be rotated outwardly about its pivot through the aperture 38 so that the globe 35 may be removed from the shade as desired. The lower end of the globe 35 is preferably provided with an aperture 39 through which air may enter, and through which dirt and the like will fall, the air escaping through the apertures 8 so that the circulation of air may be provided around the lamp.

It is obvious that when lamps of large size, as shown in Fig. 1, are used, there is danger of the shade and globe striking the lamp unless some means is provided to avoid it. This is the reason for employing the hinge structure shown. Upon referring to Fig. 1 it will be seen that if the shade and globe are swung downwardly upon the hinge taking the dotted line 40 that edge of the shade and globe opposite the hinge will strike the lamp; but after the upward extension 33 of the shade is freed from the bottom of the holder 5 the link 30 of the hinge permits the shade and globe to swing laterally so that the opposite edge takes the path indicated by the dotted line 41, whereupon the continued downward movement of the shade and globe about the hinge will describe the curved line 42 thereby clearing the lamp 34 without removing or interfering with it in any way. A protecting screen 43, preferably of reticulated material, may be secured to the periphery of the shade 27 by means of a clamping ring 44. This clamping ring is preferably chan-

nel-shape in construction embracing the edges or beads both of the shade and of the screen with an adjustable locking device, as shown more clearly in Figs. 12 and 13, for holding it in place. This catch comprises a bent member 45 secured to one end of the ring 44 with perforations 46 in its opposite sides. A pin 47 is inserted through the alined perforations and through eyes 48 of a latch member 49. This latch member 49 coöperates with a fixed catch 50 on the other extremity of the ring from which also projects a tongue 51 adapted to be inserted in the member 45 beneath the latch 49. The several perforations 46 provide the adjustment necessary for clamping the rings in position.

It is also contemplated that the globe (Fig. 5) may be connected directly to the shade or to the holder by means of a separate fastening device, as shown by Figs. 10 and 11. In this case the holder 5' has secured to it one or more fixed brackets 52 or adjustable screws 53 and is formed on one side with a perforation 54 through the holder with lugs 55 at the side thereof on the outside. A lever 56 is pivoted in the lugs 55 and has an arm 57 adapted to be engaged by a catch 58 pivotally mounted on a screw 59. In order to insert or remove the globe 35 the catch 58 is rotated as shown in dotted outline in Fig. 11, the arm 57 is depressed whereupon the globe 35 may be inserted or removed, and if inserted the lever rotated to engage the neck of the globe whereupon it may be held in place, as shown.

This construction facilitates the insertion and removal of globes and lamps and the adjustment and changing of lamps to secure the best lighting results. Not only is the lamp socket adjustable in its holder but the holder itself is adjustable so that the greatest variation may be obtained.

To prevent unauthorized removal of the clamping ring 44 and the dropping of the shade 27, seals 60 are provided, such for example as a wire loop with its ends leaded together. A wire is inserted through the catch 50 after the latch member is pressed over it to lock the ring 44, and another wire is inserted through catch 31 in a similar manner, it being necessary to break the wire or seal to open the ring or shade.

At the bottom of the globe 35 is a screen 61 larger than the aperture 39, simply laid therein and held by its own weight. This screen is to prevent the entrance of bugs and insects which gather about a light of this kind, clogging and dirtying the globe unless some means is provided to exclude them.

What I claim is:

1. An electric fixture comprising a holder with internal ridges forming a vertical guideway, a socket holder adjustable in the guideway, a lamp socket, and means for

vertically adjusting the socket in the holder independently of the position or adjustment of the said holder.

2. An electric fixture comprising a fixed holder having internal ridges forming a guide-way, a socket holder having slotted ends movable in the guide-ways, and means operable from the outside of the first named holder for adjustably clamping the socket holder in the guide-way.

10 3. In an electric fixture, the combination with a fixed holder having opposite internal guide-ways, of a socket holder slidable therein, means adjustable from the outside for clamping the socket holder in the guide-ways, and a lamp socket vertically adjustable in the socket holder.

20 4. In an electric fixture, the combination with a socket holder having an upwardly extending yoke portion, of means for holding the socket holder in position, a lamp socket slidable in the upright yoke portion, and means for clamping the socket in any adjusted position with respect to the yoke.

25 5. In an electric fixture, the combination with a socket holder having an upright yoke portion with parallel slotted sides, a socket having guide-ways adapting it to slide in the parallel sides and having apertures 30 within the guide-ways, nuts seated in the apertures, and screws extending through the slots of the yoke portion and into the nuts for adjustably securing the socket to the socket holder.

35 6. In an electric fixture, a holder, a lamp supported thereby at the bottom, a globe for inclosing the lamp, a member for holding the globe, a latch at one side of the member for engaging the holder, and a hinge attached at the other side of the member pivoted both to the member and to the holder for allowing the member to swing inwardly from the hinge in the direction of the latch so that the inside of the 45 globe opposite the hinge will clear the lamp.

7. In an electric fixture, a holder, a lamp mounted therein, a shade, a latch to engage one side of the shade with the holder, and 50 a hinge connecting the shade and holder at the opposite side and fixedly attached to the holder, adapted first to swing the shade inwardly in the direction of the latch to clear the lamp when the latch is released.

55 8. In an electric fixture, the combination of a holder, a lamp mounted therein, a shade, a latch to connect the shade and holder at one side thereof, a hinge to connect the shade and holder at the other side 60 thereof comprising a member secured to the holder, a member secured to the shade at a distance from the edge of the holder, and a link connecting the two members at the same sides and pivoted to them both.

65 9. In an electric fixture, the combination

with a holder, of a lamp supported thereby and depending therefrom, a shade, a globe supported by the shade, a latch to connect the shade and holder at one side thereof, and a hinge comprising a link pivoted at 70 its ends to the shade and holder at the other side thereof adapted to swing the opposite latched side of the shade and globe clear of the lamp when the latch is released and the shade and globe are rotated to uncover 75 the lamp.

10. In an electric fixture, the combination with an upright waterproof holder having an open lower extremity, of a globe-holding member having a portion insertible within and closely fitting the extremity, a globe insertible within said portion of the member, and means to hold the globe in position comprising one or more fixed brackets engaging the globe at one side, and a movable locking member adapted to engage the opposite side of the globe as soon as it and the members are inserted within the holder.

11. In an electric fixture, the combination with a weather-proof holder having an open lower extremity, of a shade having a portion adapted to enter and closely fit the extremity and with inwardly extending supports and an aperture in the said portion, a globe having a neck adapted to be inserted within the 90 said portion of the shade, and a locking member pivoted on the shade and movable through the aperture to engage the neck of the globe 95 opposite the supports.

12. In an electric fixture, the combination with a holder having a bottom opening, of a shade having a portion adapted to enter and closely fit the said opening and with inwardly extending supports and an aperture in the said portion, a globe having a neck adapted to be inserted within the said portion of the shade, a locking member pivoted on the shade and movable through the aperture to engage the neck of the globe 100 opposite the brackets, the locking member 105 being held in place by the holder and engaging the globe as soon as the said portion of the shade is within the holder, and releasable means for maintaining the said portion of the shade within the holder.

13. In an electric fixture, the combination with a fixed holder, a lamp supported by the holder, a shade also supported by the holder, a guard of reticulated material for the lamp, and means for securing the guard 110 to the shade comprising a single transversely divided ring having means for connecting the ends adapted to bind the edges of the guard and the shade together.

14. In an electric fixture, the combination with a holder, of a shade supported thereby, a lamp supported in the holder and projecting below the shade, a guard for the lamp having an outer diameter substantially the same as the diameter of the shade, a 125

transversely split clamping strip adapted to engage the edges of the guard and of the shade, and an adjustable locking device at the ends of the strip to bind the guard and shade together.

15. In an electric fixture, the combination with a lamp socket holder having parallel sides, and a lamp socket with outside longitudinal grooves in which the parallel sides are seated to slide the socket in the holder.

16. In an electric fixture, the combination with a yoke having parallel portions, a lamp socket with longitudinal grooves to seat said

parallel portions of the yoke whereby the socket is slideable in the yoke but held against rotation therein, and means for securing the socket in the yoke at any adjusted position.

In testimony whereof I have signed my name to this specification, in the presence of two subscribing witnesses, on this 27th day of August A. D. 1915.

GUSTAV A. HARTER.
